Primary Examiner — Patricia A Palasik(74) *Attorney, Agent, or Firm* — Abel Law Group, LLP(57) **CLAIM**

The ornamental design for a floor sanding sponge pad, as shown and described.

DESCRIPTION

FIG. 1 is a perspective view of a floor sanding sponge pad showing an ornamental design according to an embodiment of the present disclosure;

FIG. 2 is a top view of the floor sanding sponge pad of FIG. 1; and,

FIG. 3 is a bottom view of the floor sanding sponge pad of FIG. 1.

The broken lines in the drawings depict unclaimed environmental subject matter.
